UNITED STATES PATENT OFFICE.

BENJAMIN M. HARRIS, OF SAN FRANCISCO, CALIFORNIA.

STREET-TRAFFIC-CONTROLLING APPARATUS.

1,267,767.

Specification of Letters Patent. Patented May 28, 1918.

Continuation in part of application Serial No. 238,056, filed May 12, 1914. This application filed January 25, 1915. Serial No. 4,198. Renewed October 18, 1916. Serial No. 126,452.

To all whom it may concern:

Be it known that I, BENJAMIN M. HARRIS, a citizen of the United States, residing in the city and county of San Francisco and 5 State of California, have invented new and useful Improvements in Street-Traffic-Controlling Apparatus, of which the following is a specification.

This invention relates to apparatus for 10 controlling traffic at street intersections.

Traffic at congested street intersections is generally controlled by means of a changeable signal system, either audible or visible, or both, signals of one characteristic indicating one direction of traffic and signals of 15 a different characteristic indicating another and different direction of travel.

My object is to provide a mechanically operated signal device capable of variation, 20 whereby to give off a signal of a different character upon successive actuations and of like character on alternate actuations, the interval between the actuations being controlled by hand and the variation in the 25 character of the signals being produced automatically.

In carrying out this object, I provide a street traffic controlling apparatus embodying an audible signal capable of sounding 30 one and two blasts in regular succession when a signal switch or controlling member is actuated and a visible signal operating in unison therewith and actuated by the same power device. The entire mechanism is controlled by a single switch mechanism, so 35 that all the operator need do is to actuate this member in the same manner each time a change in the direction of the traffic is desired, whereupon the proper signals will occur to indicate the particular direction in 40 which the traffic is free to move.

One form which my invention may assume is exemplified in the following description and illustrated in the accompanying 45 drawings, in which—

Figure 1 is a view of the apparatus as installed.

Fig. 2 is a side elevation.

Fig. 3 is an end view.

Fig. 4 is a central vertical section.

Fig. 5 is a sectional plan of the actuating mechanism on line 5—5, Fig. 4.

Fig. 6 is a sectional detail of an intermittent clutch for the shutter mechanism.

Fig. 7 is a detail of the shutter stop. 55

Fig. 8 is a detail of the rack and pinion of the shutter mechanism.

Fig. 9 is a diagram of the electrical circuits.

Present day extreme congestions of traffic, both on street crossings and side walks, make it desirable to have a signal apparatus which can be distinctly seen by day and night, and particularly which can be arranged or located so as to be visible through 60 the largest possible angle from the desired station or point of crossing, and which will not occupy any sidewalk or street area by its support thereon.

To that end, my present invention includes a simple casing or housing 2 to which may be connected any suitable aerial suspension structure, as cables 3, which in turn may be fastened to any convenient supports, as, for instance, trolley guys, poles, building 65 walls, etc. Turnably mounted on the housing is a hollow, double-pointed direction indicator 4 with signs "stop" on opposite sides and inclosing an illuminating means, as electric lights 5. A beacon 6 may be provided if desired. The indicator 4 is secured to a tubular shaft 7 extending through a pendent bracket 2' of the housing 2; the shaft having a gear 8 engaged and driven by a reduction train 9. The latter is actuated by a suitable motor 10 in the housing. 70

Any suitable means may be utilized for controlling the motor for moving the indicator at desired periods from position to position, and, as here shown, includes an insulating arm 13 secured to shaft 7 and carrying a set of brushes 14—14' engaging concentric current rings 14^a and 14^b secured on an insulating plate 15, the arm also carrying connected brushes 16—16'. Brush 16 runs 75 on a concentric ring 16^a and brush 16' runs successively on a number of coördinate insulated quadrants 17—17^a and 18—18^a; diametrically opposite quadrants being electrically connected (Fig. 9). The brushes 100 14—14' are connected by wires run down through the tubular shaft to the light bulbs 5—6. The conductor rings 14^a—14^b are energized by feed wires 20—21 having a light controlling switch 22. 105

The motor 10 is connected to the current ring 16^a by a wire 23, the ring being cross connected by brush 16—16' to one or the

- other of the quadrants. Quadrants 17-17^a are energized by a wire 24 and quadrants 18-18^a are energized by a wire 25, which wires are severally connectable to the main 20 by a motor controlling switch 26. Thus when the switch 26 is thrown to the pole of either wire 24 or 25 the circuit will be completed to the quadrants thereof and the current delivered by the brush 16-16'.
- 10 As the motor drives the parts, the brush 16-16' will run off the segment by which it was energized and break the circuit, thus stopping the motor. Sparking is practically eliminated by choke coils 27 connected to small blocks 28 interposed between the adjacent ends of the quadrants. Momentum carries the motor brush 16-16' onto the next deenergized quadrant. As the manually operable motor switch is alternately thrown from wire 24 to 25 the motor is intermittently energized, and the double pointed indicator is turned in this case through an arc of 90°. The light circuit is controlled by the switch 22.
- 15 An important feature of this invention is the giving of an audible signal at or about the time when the visual signal is changed, so as to quickly draw notice to the latter. As this sign is especially designed for street traffic and is to aid police service, the audible signal here shown includes a whistle 30 attached to the housing 2 and having a tube 31 with an interposed valve 32, Fig. 5. The tube is connected to an air pump 33, the 20 piston 34 of which is driven by the shaft of the motor 10. The whistle valve 32 is connected to a lever 32', pivoted upon a convenient support, and is disposed in the path of rotation of a set of pins 35 which are secured upon the masterwheel 8 on shaft 7. These pins are so relatively disposed that the lever 32' will be actuated during one 25 quarter revolution to open the air valve to permit air to the whistle 30 and blow a single blast; and during another quarter revolution to actuate the valve and permit two, short, successive blasts of the whistle, such signals now being generally standard in traffic regulations.
- 30 During summer months heavy traffic ceases at about five or six o'clock and it is, therefore, desirable to cover the words "stop" of the apparatus after such hours so as to not interfere with the movement of traffic. Therefore, hinged to the sides of the casing 2 are shutters 36, to which are connected links 37 which in turn are connected to a cross-head 38, Fig. 4, in the hollow indicator 4. The cross-head is secured to a rod 39 extending up the shaft 7 and having at its upper end a rack 40 engaging a pinion 41 secured on a shaft 42. This shaft carries a bevel gear 43, meshing with a companion gear 44 secured on a vertical shaft 45, having on its lower end a loose gear 46 meshing with the master gear 8. Superposed on gear 46 is a clutch disk 47 having a sliding pin 48 projectible into an aperture 49 alining therewith in gear 46, and in which is an ejector 50 operative by a fixed cam 51 to 35 push the coupler pin out of interlock.
- 35 For simplicity of construction and operation the loose gear 46 is constantly driven with the gear 8 and will operate the shaft 45 only when the coupler pin 48 interlocks therewith. This interlocking is accomplished by the depression of pin 48 by a fixed spring 52, operative to press the pin down when engaged thereby and as soon as the aperture 49 rotates into alinement therewith. Hence the loose gear and the clutch disk coöperate to turn the shaft 45 and effect the elevating of the shutters to expose the words of the indicator. Since the shutters are connected to the cross-head, their weight is 40 reactive through the rod 39, and gears 43-44 to turn the shaft 45, as soon as the pin 48 is released, so that an arm 53 thereon will swing against a stop 54, Fig. 7, which serves to prevent the shutters falling after they 45 have been elevated by the shutter mechanism. The stop 54 comprises a spring-actuated armature pivoted at 55 and automatically snaps behind the arm 53 when it is mechanically driven to the position shown in Fig. 50 7, at which instant the cam 51 lifts the ejector 50 and disconnects the pin 48 from gear 46, the stop taking the weight of the shutters and their gearings.
- 55 At the time desired to drop the shutters, the armature is attracted by a magnet 56 with a circuit including a switch 57. The release of the arm 53 permits the shaft 45 and its related mechanism to turn and lower the shutters. This motion turns the coupler 55 pin 48 around under the presser spring 52 by which it will be pressed into its coördinate aperture 49 of the gear 46.
- 60 Assuming that the parts are all in initial inoperative position with the shutters down to cover the words "stop" and it is desired to operate the semaphore, then the officer at his station and in charge simply throws the motor switch 25 to either line wire 24 or 25, one of which will be in closed circuit to the motor according to the position of the collector brush 16-16'. The turning of the motor brush off of the energized quadrant will automatically break the circuit closed by the manual switch. Just as soon as the 65 gear 46 turns its aperture 49 under the spring-pressed pin 48, this will snap in and couple the disk and shaft to the gear 46. Thereupon, the latter will turn a half revolution until the cam acts on the ejector and trips pin 48, releasing the shaft 45, and this will be held by the stop 54 without further relation to the indicator mechanism operation. The pin 48 and the ejector 50 are frictionally held in their several positions.

Upon closing down operation, after certain hours, the officer simply closes the switch 57 to magnetically release the stop 54.

The indicator 4 indicates, by its parallel position with a street axis, that traffic is to move that way and is blocked by the sign reading "stop" in the cross street. As a signal for change of direction of travel, an officer throws the control switch and the 10 motor turns the indicator the desired angle, say 90°; synchronously the audible signal attracts attention and signifies a change in direction of movement.

In San Francisco, California, this apparatus has been successfully utilized and arranged to give the adopted single sound for east and west travel and two closely successive sounds for north and south travel. The 20 great advantage of the combination signal is that drivers keep moving when the sign shows clear and do not slow up to await the audible signal, as now commonly given by an officer.

For the purpose of stopping all traffic in 25 emergencies, as to make way for fire department apparatus and ambulances, etc., the semaphore's audible signal can be made to sound continuously by closing a switch 58 for cross connecting the motor circuit wires 30 24—25, so that when the control switch is in contact with either and the supplemental switch 58 closed, then the motor circuit will be continuously closed. This will cause the motor to continuously run and so sweep the 35 signal indicator and the several brushes of the collector continuously in a circle and cause the rapid sounding of the alarm.

This application is in substitution and 40 continuation of my original application No. 838,056, filed May 12, 1914.

In the present device the time of operation is controlled by hand, and this is accomplished by the manipulation of a switch member in the same manner upon each actuation. Once the machine is put in operation the variation in the character of the signals given out is taken care of automatically and the operator need pay no attention to this 45 phase of the machine. The fact that the operator himself cannot control the variation in the character of the signals eliminates any possibility of the signals being confused.

Various changes in the construction and 50 arrangement of the several parts herein shown and described may be employed without departing from the spirit of my invention as disclosed in the appended claims.

The present application is a continuation 55 of one filed by me on May 12, 1914, Serial Number 838,056, entitled "Traffic semaphore", and which on August 4, 1915, was formally abandoned in favor of the present application. Said prior application showed 60 and described a street traffic controlling ap-

paratus employing an audible and a visible signal variable in character for indicating a change in the direction of traffic, and means for actuating the said signals at any desired intervals to automatically indicate 70 different directions on the successive actuations.

Having thus described my invention, what I claim and desire to secure by Letters Patent, is—

75

1. In a traffic signal apparatus, a signaling device capable of producing signals of varying characteristics, means for operating the device to produce a signal of a certain characteristic, other means for operating the device to produce a signal of a different characteristic, and means for operating the signaling device to produce a third signal embodying the first two signals and to effect a continuation of the production of 85 said third signal.

2. In a traffic signal apparatus, a signaling device capable of producing signals of varying characteristics, electrical means for operating the device to produce a signal 90 of one characteristic, other electrical means for operating the device to produce a signal of a different characteristic, and means for operating the device to produce and repeat a signal combining the first two signals, 95 the latter being produced alternately relative to each other.

3. In a traffic signal apparatus, a signal, means for operating the signal, a plurality of means, each adapted for effecting independent operation of the first means to cause the production of signals of different characteristics, and a single means for effecting an operation of the first means to produce a continuous signal embodying the varying 100 signals effected by the specified plurality of means.

4. In a traffic signal apparatus, an audible signal, a plurality of electrical means for operating the audible signal to produce signals, each means being independently operable for producing a signal having characteristics differing from those of a signal produced by another of said means, and electrical means for operating the audible 110 signal to produce a signal consisting of a continuous repeating of the combined audible signals aforesaid.

5. In a traffic signal apparatus, a visible 115 semaphore, mechanism for operating the semaphore, an audible signal operable coincident with the visible semaphore, a plurality of electrical means for operating the audible signal to produce signals, each means being independently operable for producing a signal having characteristics differing from those of a signal produced by another of said means, and electrical means for operating the audible signal to produce a signal consisting of a continuous repeat- 120 125 130

ing of the combined audible signals aforesaid.

6. In combination with an audible signal including a rotary member to effect a sounding thereof, means for rotating the rotary member a predetermined degree to produce a sounding of the signal, other means for rotating said member a different predetermined degree to produce a different sounding of the signal, and a third means for continuously rotating the rotary member to produce a third and continued sounding of the signal.

7. In a traffic signal apparatus, a turnable, visible signal, electrical means for turning the signal, a shutter mounted for covering the signal to render the same invisible, and electrical means for operating the shutter to uncover the signal.

8. In a traffic signal apparatus, a movable semaphore, a whistle, fluid supplying means for the whistle, a valve for controlling the supply of fluid, means for moving the semaphore on operation of the valve, and a valve operating mechanism for opening the valve to produce alternately a single and a double blast.

9. In a traffic signal apparatus, a movable semaphore, a whistle, fluid supplying means for the whistle, a valve for controlling the supply of fluid, means for moving the semaphore on operation of the valve, and a valve operating mechanism including a trip lever to open the valve, and a rotatable member provided with a plurality of irregularly spaced pins adapted to trip the lever for effecting alternate single and double blasts.

10. In a traffic signal apparatus, a signal, a shutter movably mounted to cover the same, means to move the shutter including a shaft, a rotatable member loose thereon and provided with an aperture, a second rotatable member fixed on the shaft, a spring actuated lock pin carried by the second rotatable member and adapted to engage in the aperture of the first rotatable member to connect the two members, a slidably mounted ejecting member on the first rotatable member adapted to disengage the lock pin from the second rotatable member, a cam to actuate the ejecting member, and means to hold the shaft in its rotated position subsequent to the unlocking of the first and second rotatable members.

11. In a traffic signal apparatus, a signal, a shutter movably mounted to cover the same, means to move the shutter including a shaft, a rotatable member loose thereon and provided with an aperture, a second rotatable member fixed on the shaft, a spring actuated lock pin carried by the second rotatable member and adapted to engage in the aperture of the first rotatable member to connect the two members, a slidably mounted ejecting member on the first rotatable

member adapted to disengage the lock pin from the second rotatable member, a cam to actuate the ejecting member, and electrical releasable means to hold the shaft in its rotated position.

12. In a traffic signal apparatus, a signal, a hingedly mounted shutter adapted to cover the signal, a slidable rod, a link connecting the rod to the shutter to open the latter, and an electric mechanism for controlling the movements of the rod.

13. In a traffic signal apparatus, a casing, a signal, a tubular shaft supporting the signal from the casing, a shutter for the signal hingedly mounted on the latter, and means for operating the shutter including a rod extending from the signal through the tubular shaft to the casing.

14. A semaphore for street-crossing traffic, comprising a support, a movable semaphore carried thereby, a mechanism for moving said semaphore from one position to another, electrical means for operating the mechanism, means for limiting the movement of the mechanism to stop the semaphore in its several positions, and an audible signal device carried by said support, the operation of which is controlled by said mechanism, said device including means for rendering audible signals of different characteristics, upon successive movements of the visual semaphore.

15. A traffic signal apparatus comprising a support, a visual semaphore movably supported thereon, an audible signal carried by said support and capable of producing signals of different characteristics, upon successive movements of the semaphore, and means for moving the semaphore and producing the characteristic signal from the audible signal.

16. In a signal apparatus, a movable visible semaphore, an audible signal operable with the semaphore, and means for effecting the sounding of a single signal from the audible signal on movement of the semaphore and the sounding of a double signal from the audible signal on a successive movement of the semaphore.

17. In a signal apparatus, a rotatably mounted semaphore, means for partly rotating the semaphore, means for effecting a further part rotation of the semaphore, means for completely rotating the semaphore, an audible signal operable with the semaphore, and means associate with the aforesaid means for effecting a sounding of a certain characteristic of the signal on operation of the semaphore by the first means, a sounding of a different characteristic of the signal on operation by the second means, and a repeating of the combined soundings of the signal on operation by the third means.

18. In a street traffic signaling apparatus,

- an intermittently operating, audible signal device to automatically produce signals of different characteristics on successive actuations, and means for manually controlling the operation of said signal device. 5
19. In a street traffic signaling apparatus, an intermittently operating, audible signal device to automatically produce signals of different characteristics on successive actuations, and means for manually controlling the operation of said signal device. 10
20. In a street traffic signaling apparatus, an audible signal device and means for actuating same at any desired intervals to automatically produce signals of different characteristics on successive actuations and of like characteristics on alternate actuations. 15
21. In a street traffic signaling apparatus, an audible signal device and electrically operated means for actuating the same at any desired intervals to automatically produce signals of different characteristics on successive actuations and of like characteristics on alternate actuations. 20
22. In a street traffic signaling apparatus, an audible signal device, means for actuating the same intermittently to automatically produce signals of different characteristics on successive actuations and means for manually controlling the operation of said actuating means. 25
23. In a street traffic signaling apparatus, an audible signal device, means for intermittently actuating the same to automatically produce signals of different characteristics upon successive actuations and unitary means for manually controlling the operation of said actuating means. 30
24. In a street traffic signaling apparatus, an audible signal device, an intermittently operating motor for actuating same to automatically produce signals of different characteristics on successive actuations and means for manually controlling the operation of said motor. 35
25. In a street traffic signaling apparatus, an audible signal device, an intermittently operating motor for actuating same to automatically produce signals of different characteristics on successive actuations and a hand operated switch for controlling the operation of said motor. 40
26. In a street traffic controlling appa- 50
- ratus, an audible signal, means for intermittently actuating said audible signal to automatically produce a single blast on one actuation, whereby to indicate one direction of traffic, and a double blast on the succeeding actuation to indicate a different direction of traffic, and means for manually controlling the operation of said actuating means. 55
27. In a street traffic controlling apparatus, an audible and a visible signal variable in character for indicating a change in the direction of traffic, and means for actuating the said signals at any desired intervals to automatically indicate different directions on successive actuations. 60
28. In a street traffic controlling apparatus, an audible and a visible signal variable in character for indicating a change in the direction of traffic, intermittently operating means for actuating the said signals to automatically indicate different directions on successive actuations, and manually operated means for controlling the operation of said actuating means. 65
29. In a street traffic controlling apparatus, an audible signal, means for actuating the same and controlling means for said actuating means, whereby to automatically produce intermittently one and two blasts in regular succession at any desired intervals to indicate different directions of traffic, and controlling means for said actuating means, whereby to produce continuously a succession of one and two blasts. 70
30. In a street traffic signaling apparatus, a whistle, a turnable indicator, actuating means for the same and controlling means for said actuating means, whereby to automatically produce, at any desired interval, one and two blasts of the whistle on successive actuations and a change of direction of the indicator in accordance therewith and controlling means for said actuating means, whereby to produce continuously a succession of one and two blasts of the whistle and a continuous movement of the indicator. 75
